[57] **CLAIM**

The ornamental design for an auxiliary vehicle light, as shown and described.

DESCRIPTION

FIG. 1 is a front view of an auxiliary vehicle light showing my new design.

FIG. 2 is a rear view of the auxiliary vehicle light shown in FIG. 1.

FIG. 3 is a top view of the auxiliary vehicle light shown in FIG. 1.

FIG. 4 is a bottom view of the auxiliary vehicle light shown in FIG. 1.

FIG. 5 is a left side view of the auxiliary vehicle light shown in FIG. 1.

FIG. 6 is a right side view of the auxiliary vehicle light shown in FIG. 1; and,

FIG. 7 is a top and left side perspective view of the auxiliary vehicle light shown in FIG. 1.

The broken lines are shown for illustrative purposes only and form no part of the claimed design.
